UNITED STATES PATENT OFFICE.

PAUL L. CROWE, OF BALTIMORE, MARYLAND.

GRINDING AND SEPARATING APPARATUS.

Application filed October 20, 1925. Serial No. 63,742.

This invention relates to mills for grinding and separating materials, and has particular reference to a mill for grinding and separating ores, coal and similar materials.

5 The primary object of the present invention is to provide a particularly simple and highly efficient form of apparatus for grinding materials and simultaneously effecting a separation of the lighter or finely divided

10 particles from the heavier or larger particles.

Another object is to provide an apparatus of this character which shall consist of a rotary member composed of a plurality of grinding elements, and one or more stationary elements disposed in operative relation thereto for feeding the materials and also for cooperating with said rotary member to effect a grinding of the material, there being also pneumatic means associated with the 15 grinding members to effect the aforementioned separation.

A further object is to provide an apparatus of the aforesaid character which shall be simple in construction, inexpensive to 20 manufacture and which shall be highly efficient in operation.

With these and other objects in view, the invention may be stated to consist in the various novel features of construction and arrangement or combination, all of which will 25 be fully described hereinafter and pointed out in the appended claims.

In the accompanying drawings, wherein I have shown certain illustrative embodiments of my invention, but without intent 30 to limit myself, except as set forth in the appended claims,

Fig. 1 is a longitudinal sectional view through a crushing and separating apparatus constructed in accordance with my invention; Fig. 1^a is a fragmentary longitudinal sectional view showing a slight modification;

Fig. 2 is a vertical sectional view taken on 40 the line 2--2 of Fig. 1;

Fig. 3 is an end elevation of the apparatus;

Fig. 4 is a longitudinal sectional view of a portion of a modified form of apparatus;

50 Figs. 5, 6 and 7 are transverse vertical sectional views each illustrating a still further modification;

Fig. 8 is a side elevation of a crusher plate such as used in the modification shown in 55 Fig. 7;

Figs. 9 and 10, are, respectively, side and

end elevations of a modified form of crusher plate;

Figs. 11 and 12 are, respectively, fragmentary vertical sectional and top plan views 60 of a modified form of grinding ring;

Fig. 13 is a vertical sectional view of a further modified form of grinding ring; and

Fig. 14 is a vertical sectional view taken 65 on the line 14--14 of Fig. 1.

Describing the various parts by reference characters, and referring particularly to Figs. 1-3, inclusive, 1 denotes a suitable base, from which rise end walls 2 and 3, and a partition plate 5, the latter extending longitudinally of the base and substantially midway 70 of the end walls. Extending longitudinally through the end walls is a tubular shaft 6 which is formed with radially disposed ribs 7 that are adapted to receive and support a 75 plurality of grinding rings 8 to be referred to hereinafter.

One end of hollow shaft 6 projects through end plate 3 and is journaled in a bearing cap 9, having oppositely projecting lugs 10 80 which are secured to said end plate by bolts 11 or other suitable fastening means. The opposite end of hollow shaft 6 projects through end plate 2 and diverges radially 85 to form a circular plate 12. This plate carries a series of vanes 14 curved in one direction on one side thereof, and a second series of vanes 15, curved in an opposite direction, on the opposite side thereof, as clearly shown in Fig. 14. A housing 16 encloses the fan 90 member and an extension 17 thereof is journaled in an anti-friction bearing 18, which is carried by end plate 2. A drive pulley 19 is formed on the housing 16 so that power 95 from any suitable source may be connected therewith.

Mounted on the aforementioned ribs 7 are a plurality of the grinding rings 8, each placed in close contact with an adjacent ring to define a grinding cylinder and this cylinder and hollow shaft 6 form what might be termed a double hollow shaft. Each of the rings 8 may be circular in shape and is provided with suitable notches 20 to receive ribs 7, and also with a plurality of apertures 21, the latter being preferably formed with a narrow or restricted central portion and outwardly diverging outer and inner end portions, as shown in Fig. 1. The shape of 105 these apertures permits ground material to readily enter and leave without the danger of clogging, and the restricted central por-

tion limits the size of material passing therethrough.

In Fig. 13, I have shown a modified form of grinding ring 8^a wherein the aperture 21^a 5 are substantially frusto-conical in shape and it will be understood that rings of this character, or similar to that shown in Figs. 11 and 12 and to be described hereinafter might be used equally well.

10 Disposed about the grinding rings are a pair of feeding and crushing plates 25 and 26, each pivoted adjacent its upper end to the end walls 2 and 3 by bolts 27 or other suitable fastening means. Plate 25 is arcuate in cross section, as shown in Fig. 2 and is formed with end walls 28. The lower edge of this plate is preferably extended inwardly to a point adjacent the grinding rings or cylinder, and a wear plate 29 is fastened to the concave side thereof. Crusher plate 26 is formed with a downwardly curved side wall 30, which terminates in an upwardly curved end portion that extends in close proximity to the grinding rings. A 15 wear plate 31 is also fitted thereto, as shown in Fig. 2. Plate 26 is also formed with a second side wall 32 which extends from the upper inner edge in close proximity to the grinding rings, thence downwardly and outwardly therefrom, and this wall is also provided with a wear plate 33 on the surface adjacent the grinding rings. End walls 34 and the aforementioned side walls 30 and 32 define a feed hopper for feeding material to the grinding rings.

In order to assist the plates 25 and 26 in feeding the material to the grinding rings, I provide means for oscillating said plates during operation of the apparatus. 20 A cam 36 is mounted on the aforementioned ribs 7 between a pair of grinding rings 8 and this cam engages a shoe 37, as shown in Figs. 1 and 2. It will be noted in this connection that the lower edge portion of each of plates 25 and 26 is slotted as shown in dotted lines in Fig. 2 to allow the cam to rotate freely and without engagement therewith. Pivottally connected with shoe 37 and extending in opposite directions, are a pair 25 of arms 38, each of which extends through a lug 39 formed on wear plates 25 and 26. A coil spring 40 is applied to the outer end of each of these arms, and a nut 41 screwed thereon serves to regulate the tension of the 30 spring.

In practice, I preferably magnetize the grinding rings 8 so that these rings will serve to separate iron and steel and similar particles from the materials being ground. 35 The material to be ground is dumped into the top of the apparatus and will be fed downwardly through the hopper defined by side walls 30 and 32 of plate 26, and also by the side wall 29 of plate 25. It will be assumed that power will be applied to pulley

19 to rotate shaft 6 in a clockwise direction, as viewed in Fig. 2. Rotation of casing 16 with fan blades 14 and 15 will also rotate grinding rings 8, and these rings in connection with the lower end portions of plates 29 and 31 will effect a crushing and grinding action on the material. Meanwhile, fan blades 14 will create a suction through the longitudinal passages defined by ribs 7, and thereby pull the finely divided or ground material through apertures 21 and into fan casing 16. The fan blades 15, being curved in an opposite direction to blades 14, receive the finely divided material and force it to the center of rotation thereof and thence through shaft 6 where it may be conveyed to any desired point. The rotation of grinding rings 8 and cam 36 serve to oscillate plates 25 and 26 about their pivot points 27, and the provision of the yielding connection 40 between arms 38 and the aforementioned plates permits the larger particles of unground material to pass between the plates and the rings and be deposited on the right-hand side of partition plate 5, as viewed in Fig. 2. Any impurities, such as iron or steel scrap will adhere to the magnetized grinding rings 8 and will be carried beyond the partition plate 5, whereupon they will drop by gravity to the lefthand side of said partition, as they start upwardly.

As a modified driving means for the apparatus, I have indicated by dotted lines in Fig. 1 a series of pole pieces 42 formed on the periphery of the fan casing 16, or on the face thereof, or on both surfaces so that said casing may be either the field or the armature of a motor which surrounds the fan casing. In connection with this type of drive I also connect a small generator 42^a to the fan casing so as to be rotatable therewith. This generator may serve as an exciter for the field of the driving motor, or the output thereof may be used as part of the current required for driving the motor and thus lessen the current normally drawn from the line.

In Fig. 1^a I have shown a slightly modified form of construction wherein the tubular shaft 6^a is formed with an annular collar 6^b that is provided with a plurality of apertures 6^c. A ball bearing assembly 6^d is carried by collar 6^b and abuts against rings 8. Enclosing the bearing structure is a cap 9^a which is fastened by screws 11^a to end wall 3, and this cap is provided with a plate 9^b which is formed with apertures (not shown) that are adapted to align with apertures 6^c upon rotation thereof. With this arrangement I am enabled to either shut off the air supply through apertures 6^c or regulate such air supply to any desired degree. In other respects the apparatus is similar to that shown in Fig. 1.

120 In Fig. 4, I have shown a modified form

of apparatus which consists of a centrally disposed fan casing 16^a, from each side of which projects a hollow shaft 6^a. These shafts are provided with longitudinally disposed ribs 7^a that are adapted each to receive a plurality of grinding rings and a cam, as above described in connection with Fig. 1. This form of apparatus will have double the capacity of the device shown in Fig. 1, and the operation thereof will be similar to that previously described.

In Fig. 5, I have shown a modified arrangement for connecting the lower ends of the plates 25^a and 26^a. In this instance, a bar 43 is fastened rigidly to partition plate 5^a by nuts 44 or other suitable fastening means. Bar 43 extends through enlarged apertures in lugs 45 which depend from the lower ends of plates 25^a and 26^a. A nut 46 is applied to each end of bar 43, and a spring 47 is interposed between said nut and the lugs 45 to provide a yielding connection between the bar and plates. In this form of apparatus, the aforementioned cam 36 has been dispensed with and the tension of springs 47 is depended on to exert the necessary pressure on the material being ground by the rings and ends of the plates. In other respects, the apparatus is identical with that shown in Fig. 1.

In Fig. 6, I have shown a further modification of the crushing plates. In this form, a pair of crushing plates 50 are each pivoted to end walls 2^a. These plates are each provided with a series of crushing rollers 51, journaled between the end walls 52 of said plates. As shown in Fig. 6, the upper of these rollers is spaced a greater distance from the grinding rings 8^a than the intermediate and lower rollers. This arrangement permits the material to be partially ground or crushed by the upper rollers and progressively ground finer as it passes the intermediate and lower rollers. A yielding connection between the plates 50 may be employed similar to that described in connection with Fig. 5, or, if desired, a connection similar to that shown in Fig. 1 may be used.

In Fig. 7, I have shown a still further modification wherein I provide a pair of downwardly converging side plates 53, each of which is pivoted at 54 to the end walls. The lower end portions of these plates are disposed in close proximity to the grinding rings 8^a, thereby to effect a crushing or grinding of the material passing therebetween. In order to partially grind the material before it reaches these points, I preferably arrange a pair of rollers 55 thereabove. These rollers extend between the said plates 2^a of the apparatus and are spaced somewhat from the grinding rings 8^a. The lower ends of plates 43 are shown yielding connected similar to that disclosed in connection with Fig. 5, but it will

be understood that a yielding connection, similar to that employed in the apparatus shown in Fig. 1 might be used equally well. In connection with Fig. 7, I wish also to point out that plates 53 are each identical in construction and are also reversible. Each end portion of these plates is provided with a wear surface 56 on each side thereof, and each corner of these plates is formed with a spherical projection 57. Each spherical projection is provided with two bores arranged at right angles to each other. One of these bores is adapted to receive pivot bolt 54, while the other is adapted to receive the bar 43^a. In Figs. 9 and 10, I have shown a modified form of crushing plate 60, which could be used on either side of the crushing rings, but which could not be turned upside down, as is the case with the plate shown in Fig. 8. Each plate 60 is provided with a pair of lugs 61 that are adapted to receive a pivot bolt, as previously described. The lower end portions of these plates may be fitted with a wear plate 62, if desired, and a lug 63 projects from the central portion thereof to permit the plates to be yieldingly connected, similar to the forms previously referred to.

In Figs. 11 and 12, I have shown a modified form of grinding ring, wherein the outer peripheral surface of each ring is formed with a plurality of tangentially extending teeth or projections 65. Intermediate each tooth or projection, I provide a plurality of tapered apertures 66, which are preferably arranged with their smaller ends at the outer periphery of the ring. These rings may be used with any of the various forms of apparatus previously described.

From the foregoing description, it will be obvious that I have provided an exceedingly simple and easily constructed grinding and separating machine, wherein the finely divided material is withdrawn at one point and the coarser materials and impurities are each separated and discharged at different points.

What I claim is:—

1. An apparatus of the character set forth comprising a base, a grinding cylinder journaled on said base and having a plurality of apertures therein, a crusher plate disposed in operative relation to said cylinder, means for yieldingly urging said crusher plate toward said cylinder and means for creating an air draft through the apertures in said cylinder to withdraw the finely divided material therethrough.

2. An apparatus of the character set forth comprising a base, a grinding cylinder journaled on said base and having a plurality of apertures therein, a pair of crusher plates disposed in operative relation to said cylinder, means for yieldingly urging said plates

- 5 toward said cylinder, and means for creating an air draft through the apertures in said cylinder to withdraw the finely divided material therethrough.

5 3. An apparatus of the character set forth comprising a base, a grinding cylinder journalled on said base, said cylinder being composed of a plurality of rings each having a plurality of apertures therein, a pair of crusher plates disposed in operative relation to said cylinder, means for yieldingly urging said plates toward said cylinder, and means for creating an air draft through said apertures to withdraw the finely divided material therethrough. 10

15 4. An apparatus of the character set forth comprising a base, a grinding cylinder journalled on said base and provided with a plurality of apertures, said cylinder being magnetized to attract iron and steel impurities, a partition plate rising from said base and disposed in close proximity to the lower surface of said cylinder, a pair of crusher plates disposed in operative relation to said cylinder, means for yieldingly adjusting said plates toward said cylinder, and means for creating an air draft through the apertures in said cylinder to withdraw the finely divided material therefrom. 20

25 5. An apparatus of the character set forth comprising a base, a grinding cylinder journalled on said base and having a plurality of apertures therein, a tubular shaft projecting through said cylinder, a pair of crusher plates disposed in operative relation to said cylinder, and means for creating an air draft through the apertures in said cylinder and through said tubular shaft. 30

35 6. An apparatus of the character set forth comprising a base, a grinding cylinder journalled on said base and having a plurality of apertures therein, a tubular shaft projecting through said cylinder and having the walls thereof spaced from the walls of said cylinder, a pair of crusher plates disposed in operative relation to said cylinder, means for creating an air draft through the apertures in said cylinder to withdraw the finely divided material therethrough, and means for directing said material through said tubular shaft. 40

45 7. An apparatus of the character set forth comprising a base, a grinding cylinder journalled on said base and having a plurality of apertures therein, a tubular shaft projecting through said cylinder and having the walls thereof spaced from the walls of said cylinder, a pair of crusher plates disposed in operative relation to said cylinder, operative means for yieldingly adjusting said plates toward said cylinder, a partition plate rising from said base to a point adjacent said cylinder, means for creating an air draft through the apertures in said cylinder to withdraw the finely divided material therethrough, and means for directing said material through said tubular shaft. 50

55 8. An apparatus of the character set forth comprising a base, a grinding cylinder journalled on said base, said cylinder being composed of a plurality of rings each having a plurality of apertures therein, a tubular shaft projecting through said cylinder and having a plurality of radially disposed vanes engaging said rings, and defining passages, means for creating an air draft through said passages and apertures to withdraw finely divided material therethrough, and means for directing said material through said tubular shaft. 60

65 9. An apparatus of the character set forth comprising a base, a grinding cylinder journalled on said base, said cylinder being composed of a plurality of rings each having a plurality of apertures therein, a shaft projecting through said cylinder and having a plurality of radially disposed vanes engaging said rings and defining passages, and a fan carried by said shaft and adapted to create an air draft through said apertures and passages to withdraw the finely divided material therethrough. 70

75 10. An apparatus of the character set forth comprising a base, a grinding cylinder journalled on said base, said cylinder being composed of a plurality of rings each having a plurality of apertures therein, a hollow shaft projecting through said cylinder and having a plurality of radially disposed vanes engaging said rings and defining passages, a fan carried by said shaft and adapted to create an air draft through said apertures and passages to withdraw the finely divided material therethrough, and a second fan carried by said shaft and adapted to direct said material through said hollow shaft. 80

85 11. An apparatus of the character set forth comprising a base, a grinding cylinder journalled on said base, a cam carried by said cylinder, a pair of crusher plates disposed in operative relation to said cylinder, a yielding connection between said plates, means carried by said connection and engaged with said cam to oscillate said plates, and means for rotating said cylinder. 90

95 12. An apparatus of the character set forth comprising a base, a grinding cylinder journalled on said base, said cylinder being composed of a plurality of rings each having a plurality of apertures therein, a tubular shaft projecting through said cylinder and having a plurality of radially disposed vanes engaging said rings and defining passages, a cam ring carried by said vanes, a pair of pivotally mounted crusher plates disposed in operative relation to said cylinder, a yielding connection between said plates, a shoe carried by said connection and engaged with said cam, a fan carried by said shaft and adapted to create an air draft through said 100

105 110

115 120

125 130

apertures and passages to withdraw finely divided material therethrough, and a second fan carried by said shaft and adapted to direct said material through said hollow 6 shaft.

13. An apparatus of the character set forth comprising a base, a grinding cylinder journalled on said base, a pair of crusher plates disposed in operative relation to said 10 cylinder, each of said plates being provided with a plurality of rollers disposed at variable radii with respect to the center of said cylinder, and means yieldingly connecting said plates and normally urging the same 15 toward said cylinder.

14. In an apparatus of the character set forth, the combination of a double hollow shaft, grinding elements associated with the outer of said shafts, said outer shaft being 20 provided with a plurality of apertures, crushing plates disposed about said hollow shafts, means for yieldingly urging said plates toward said grinding elements, and pneumatic means for directing the ground

material through the inner of said hollow 25 shafts.

15. In an apparatus of the character set forth, the combination of a double hollow shaft, grinding means associated with the outer of said hollow shafts, said outer shaft 30 being provided with a plurality of apertures, crusher plates disposed about said hollow shafts and having a portion thereof disposed in close proximity to said grinding means, and means for yieldingly urging said 35 plates toward said grinding means.

16. In an apparatus of the character set forth, the combination of a double hollow shaft, grinding means associated with the outer of said hollow shafts, said outer shaft 40 being provided with a plurality of apertures, and a pair of crusher plates disposed about said hollow shafts, each of said crusher plates having rollers disposed at variable distances from said grinding means. 45

In testimony whereof I affix my signature.

PAUL L. CROWE.
